(57) **CLAIM**

The ornamental design for a mechanoreception stimulation ball, as shown and described.

DESCRIPTION

FIG. 1 is a diagonal elevation view of the ornamental design for a mechanoreception stimulation ball;

FIG. 2 is a front elevation view of the design;

FIG. 3 is a rear elevation view of the design;

FIG. 4 is a top elevation view of the design;

FIG. 5 is a bottom elevation view of the design;

FIG. 6 is a left side elevation view of the design;

FIG. 7 is a right side elevation view of the design;

FIG. 8 is elevation view of the design showing the ball halved to show an interior wherein a smaller ball is centrally disposed therein;

FIG. 9 is elevation view of the design showing the ball halved to review an interior and the smaller ball removed from a central cavity interior to the ball;

FIG. 10 is a diagonal elevation view of the design showing interior faces of the ball when halved;

FIG. 11 is a front elevation view of the design showing the ball halved and placed upon a surface; and,

FIG. 12 is a front elevation view of the design showing the ball halved and placed inverted upon a surface.

The broken lines shown are for the purpose of illustrating portions of the mechanoreception stimulation ball, which form no part of the claimed design.
